ATTORNEY

UNITED STATES PATENT OFFICE.

PEARL B. MCKENZIE, OF SEDALIA, MISSOURI.

BRACELET.

Application filed October 31, 1921. Serial No. 511,722.

To all whom it may concern:

Be it known that I, PEARL B. MCKENZIE, a citizen of the United States, residing at Sedalia, in the county of Pettis and State of Missouri, have invented new and useful Improvements in Bracelets, of which the following is a specification.

This invention comprehends the provision of a bracelet attachment designed for the purpose of holding the handkerchief attached to the bracelet.

The nature and advantages of the invention will be better understood when the following detailed description is read in connection with the accompanying drawing, the invention residing in the construction, combination, and arrangement of parts as claimed.

In the drawing forming part of this application, like numerals of reference indicate similar parts in the several views and wherein:—

Figure 1 is a perspective view of a bracelet, showing the attachment associated therewith.

Figure 2 is an enlarged fragmentary view of the bracelet, partly in section, showing the invention.

Figure 3 is a transverse sectional view through the bracelet, showing the slide in end elevation.

Figure 4 is a detail view of the attachment.

Figure 5 is a similar view of the wedge-shaped locking element.

Referring to the drawings in detail, 10 indicates a bracelet of well known construction with which the device forming the subject matter of the invention is adapted to be associated.

The invention is in the nature of an attachment designed for holding a handkerchief secured to the bracelet, and consists of a substantially U-shaped resilient element as illustrated in Figure 4. The limb 11 of this element is terminally secured to one portion of the bracelet 10 within the latter, while the remaining limb 12 is arranged exteriorly of the bracelet, after being passed through an opening 13. The limbs 11 and 12 are slightly curved to conform to the curvature of the bracelet.

In connection with the U-shaped element, I employ a locking device of the character illustrated in Figure 5, and which device consists of a substantially wedge-shaped member 14, from which projects a pin 15 having a knob 16. The wedge-shaped member operates between the limb 11 of the resilient element and the adjacent wall of the bracelet, and is arranged to slide longitudinally of the limb 11 for a purpose to be presently stated. The pin 15 projects through a slot 17 in the bracelet. When the locking member is shifted in one direction, the resilient element is permitted movement with relation to the bracelet, so that a handkerchief may be placed between the limb 12 and the bracelet 10, after which the locking element is shifted in an opposite direction to hold the element fixed relatively to the bracelet, and thereby hold the handkerchief attached to the latter. The invention is simple in construction and can be used in connection with bracelets of well known construction.

While it is believed that from the foregoing description the nature and advantages of the invention will be readily apparent, I desire to have it understood that I do not limit myself to what is herein shown and described, and that such changes may be resorted to when desired as fall within the scope of what is claimed.

What I claim is:—

1. A bracelet attachment of the character described comprising a substantially U-shaped element having one limb secured within the bracelet and its other limb arranged exteriorly thereof, said bracelet having a slot, a wedge-shaped element slidable within the bracelet along the first mentioned limb, a pin projecting from the said wedge-shaped element through said slot for controlling said wedge-shaped element, and said element when in one position holding the second mentioned limb in clamping relation to the bracelet for the purpose specified.

2. A bracelet attachment of the character described, comprising a member having a portion disposed within the bracelet and a portion disposed exteriorly thereof and spaced therefrom, and means slidable within the bracelet and cooperating with said

member to hold the exterior portion thereof in gripping relation with the bracelet for the purpose specified.

3. A bracelet attachment of the character described comprising a member having a portion arranged within the bracelet and a portion arranged exteriorly thereof and spaced therefrom, and a wedge-shaped mem-

ber arranged to slide within the bracelet and cooperate with said member to hold the latter mentioned portion thereof in gripping relation with the bracelet for the purpose specified. 10

In testimony whereof I affix my signature.

PEARL B. MCKENZIE.
